UNITED STATES PATENT OFFICE.

PEDER O. STANGELAND, OF LOS ANGELES, CALIFORNIA.

TOOL HOLDER.

1,416,904.

Specification of Letters Patent. Patented May 23, 1922.

Application filed March 29, 1920. Serial No. 369,507.

To all whom it may concern:

Be it known that I, PEDER O. STANGELAND, a citizen of the United States, residing at Los Angeles, in the county of Los Angeles, 5 State of California, have invented new and useful Improvements in Tool Holders, of which the following is a specification.

This invention relates to tool holders and more specifically to wood scraper holders, 10 and the like. An object of the invention is to provide a simple, effective, and inexpensive device for holding wood scrapers, saws, etc.

A particular feature of the invention is 15 the provision of a tool holding device which can be quickly and easily operated to grip or release a tool. This feature of the invention is important in that it makes the device convenient and simple to operate 20 thereby making it of great commercial value.

An object of the invention is to provide a 25 device of the character specified in which there are no bolts, catches, or like devices, that engage the tool in order to hold it. The device embodies a wedge which is adapted to be actuated by a nut to clamp the holder on, or release it from, the tool.

A further feature of the invention is the 30 simple, compact, and neat construction of the holder. The tool holder in being compact and neat is not only slightly but is particularly convenient to handle. The holder may be easily and inexpensively constructed 35 so that it affords a smooth and convenient grip for the hands of the operator.

There are further objects and features of 40 the invention which will be best understood from the following detailed description of typical embodiments of the invention throughout which reference is had to the accompanying drawings, in which—

Fig. 1 is a perspective view of a form of holder particularly adapted for holding 45 scrapers, showing the manner in which it may be conveniently gripped by the hands of an operator; Fig. 2 is an enlarged vertical central section through the device shown in Fig. 1; Fig. 3 is a perspective view of the 50 wedge employed in the holder shown in Figs. 1 and 2, being a view of the wedge removed from the rest of the holder; and Fig. 4 is a front elevation of a portion of the holder 55 with some of the parts broken away for sake of clearness.

In the drawings, the invention is shown

as embodied in a scraper holder. Throughout the drawings numeral 10 designates the body of the holder which is formed with a recess or groove 11 adapted to receive the 60 scraper 12. The body 10 of the holder is preferably formed of wood and is provided with a suitable handle 13. The body 10 of the scraper and also the handle 13 present smooth regular surfaces that can be conveniently and effectively gripped by an operator's hand as indicated by the dotted lines in Fig. 1.

The scraper 12, as shown throughout the drawings, is a flat piece of steel provided 70 with a sharpened or properly turned edge 14. The groove 11 in the body 10 is preferably sufficiently wide to receive the scraper 12 and sufficiently deep to cause the cutting, or sharpened, edge 14, of the scraper, to extend somewhat beyond the holder when the scraper is in place in the slot, as shown in Figs. 1, 2 and 4.

When the scraper 12 has been arranged in the groove 11, in the position desired by the 80 operator, it can be firmly and effectively held or clamped, in that position by the movement of wedge 15 upwardly between the front side 16, of a frame or band 17, and the front side of the body 10. The band 85 17 is a metal member having a side 18 which engages the rear side of the body 10, a front side 16 which is engaged by the wedge 15, and ends 19 which connect the ends of sides 16 and 18 and engage the ends of the 90 body 10, in the manner clearly shown in the drawings. The band 17, it will be noted, is arranged around the grooved portion of the body 10 so that when the wedge 15 is moved upwardly, between the body and side 16 95 of band 17, it causes the grooved portion of the body 10 to firmly grip, or be clamped onto, the scraper 12 thereby positively gripping it and preventing it from becoming displaced. Due to the body 10, of the 100 scraper, being formed of wood the wedge 15 is particularly effective in clamping the grooved portion of the body onto the scraper. The band 17 may be prevented from becoming displaced from the body 10, 105 in any suitable manner, for instance, suitable wood screws 20 may be arranged through the side 18, of the band, so as to extend into the body 10, as shown in Fig. 2 of the drawings.

To move the wedge 15, either upwardly so as to cause scraper 12 to be gripped in

the manner just described, or downwardly so as to cause the scraper to be released the operator turns or rotates a nut 21 screw threaded on a rod 22 which is connected directly to the wedge 15. The rod 22 is preferably connected to the wedge 15 by rivets 23 and is shaped to extend inwardly from the wedge 15 through a recess 24 in the body and then upwardly through a bore 25 in the handle 13. The free or outer end of the rod 22 projects, or extends, from the upper end of the handle 13 and is screw threaded to carry the nut 21. The nut 21, although accessible and free to be rotated is held against longitudinal displacement by a metal strap 26 secured to the upper end of handle 13 by suitable screws 27. The strap 26 positively holds the nut 21 between it and the end of the handle 13 thereby preventing the nut 20 from moving longitudinally when it is rotated. It will be readily understood how rotation of the nut 21 causes longitudinal movement of the rod 22 in bore 25 thereby causing movement of the wedge 15. The direction in which the wedge 15 is moved depends, of course, upon the direction in which the nut 21 is rotated, and the force with which the wedge 15 is moved, that is, the force with which it is drawn between the band 17 and body 10, depends upon the force with which the nut 21 is turned. It is preferred that washers 29 be carried on the rod 22 between the end of handle 13 and the nut 21 and also between the strap 26 and the nut 21, as clearly shown in Fig. 2. It will also be noted in the drawings, particularly in Fig. 2, that the recess 24 is sufficiently large to allow proper movement of the rod. The full lines in Fig. 2 show the

wedge 15 and the rod 22 in the extreme up position, or in the position where the wedge is drawn tightly between the band and body, while the dotted lines in Fig. 2 indicate the down position of the wedge 15 and rod, or the position to which the wedge 15 is moved relative to the frame 17 to allow of the scraper 12 to be placed in or removed from the groove 11.

Having set forth preferred embodiments of my invention I do not wish to limit or restrict myself to the particular details hereinabove set forth but wish to reserve to myself any changes or variations that may appear to those skilled in the art or that may fall within the scope of the following claim.

Having described a preferred form of my invention, I claim:

A tool holder comprising a body formed with a groove to receive a tool, a handle on the body, a band extending around the grooved portion of the body, a wedge lying between the band and the body and movable in a direction longitudinal of the handle to cause gripping of the tool, a rod connected to the wedge and extending longitudinally through the handle, the body being slotted and the handle having a longitudinal bore to pass the rod, the end portion of the rod being screw-threaded, and a nut at the end of the handle threaded on the rod.

In witness that I claim the foregoing I have hereunto subscribed my name this 22d day of March, 1920.

PEDER O. STANGELAND.

Witness:

VIRGINIA BERINGER.
